COUNTER PRESSURE COOKER

Edward J. Nelson, Omaha, Nebr., assignor to Ballantyne
Instruments and Electronics, Inc., Omaha, Nebr., a cor-
poration of Delaware

Filed Sept. 14, 1962, Ser. No. 71,687

Term of patent 14 years

(Cl. D81—10)

FIG. 1.

FIG. 2.

FIG. 3.

FIG. 4.

FIGURE 1 is a front perspective view of a counter pressure cooker, showing my new design.

FIGURE 2 is a perspective view of the left side.

FIGURE 3 is a perspective view of the rear.

FIGURE 4 is a perspective view of the right side.

The vertical door panel and the slightly inclined control panel in FIGURE 1 are shaded to indicate contrasting areas.

I claim:

The ornamental design for a counter pressure cooker, as shown and described.
